SUSIE J. MERCER, Primary Examiner

C. KEMPER, Assistant Examiner

FIG. 1 is a perspective view of an electronic calculating machine showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof; and

FIG. 7 is a left side elevational view thereof.

The broken line disclosure of the numerals in FIG. 1 is for illustrative purposes only and forms no part of the claimed design.

I claim:

The ornamental design for an electronic calculating machine, as shown and described.
